GUIDE

Julius M. Goldberg, New York, N. Y.

Application February 12, 1952, Serial No. 18,493

Term of patent 14 years

(Cl. D61—1)

To all whom it may concern:

Be it known that I, Julius M. Goldberg, a citizen of the United States, residing at New York, in the county of New York and State of New York, have invented a new, original, and ornamental Design for X-Ray Film Holder and Directional Guide, of which the following is a specification, reference being had to the accompanying drawings, forming part thereof.

Figure 1 is a front perspective view of my design for an X-ray film holder; and

Figure 2 is a rear perspective view thereof.

I claim:

The ornamental design for an X-ray film holder and directional guide, as shown.

JULIUS M. GOLDBERG.
